STARTING BLOCK

Elwood M. Miller, Reinbeck, Iowa

Application November 26, 1948, Serial No. 62,081

3 Claims. (Cl. 272—59)

1

This invention relates to starting blocks used in connection with athletic running tracks.

It is an object of the present invention to provide a starting block which is easily attachable to the ground or can be removed therefrom in an easy manner, wherein the gripping elements are a part of a lever which can be depressed to engage the elements with the ground or which by depressing an arm can be elevated, whereby to eliminate the need for a hammer and spikes for the securing of such blocks to the ground.

Other objects of the present invention are to provide a starting block which is of simple construction, light in weight, has long life, easy to handle, easy to set up or remove, inexpensive to manufacture and efficient in operation.

For other objects and for a better understanding of the invention, reference may be had to the following detailed description taken in connection with the accompanying drawing, in which

Fig. 1 is a top plan view of the starting block embodying the features of the present invention.

Fig. 2 is a longitudinal sectional view of the starting block taken on line 2—2 of Fig. 1.

Fig. 3 is a front elevational view of the starting block.

Referring now to the figures, 10 represents a base, made preferably of aluminum and having a raised and rearwardly inclined portion 11 which has an opening 12 therein across which there is extended a basket weave or knurled finish 13 against which the foot of the runner is placed. This surface will provide adequate support for the foot and the foot will not be readily slid thereover.

At the rear of the base 10 are upstanding lugs 14 and 15 between which is extended a rod 16. A lever 17 is connected to the rod to pivot thereon and this lever when it is tilted in one direction will extend gripping spikes 18 through openings 19 in the base 10 and into the ground as shown in Fig. 2. Spikes 18 are curved and are pointed at their ends as indicated at 21. When the spikes are extended into the ground, arm 22 of the lever carrying the spikes lies flush upon the base 10. Another arm 23 extends rearwardly and upwardly and serves as a release arm against which the foot can be placed to lift the arm 22 and the spikes 21 out of the ground. When the spikes are extended into the ground, the foot is placed on the arm 22.

The blocks are placed on the track in the desired position. The runner or his trainer then steps on the lever at the base of the block, this

2

lever drives the curved spikes, which are attached to it, into the ground. These spikes securely hold the block in place. After the runner has started, the blocks may be removed in a simple and efficient manner by stepping on the angled arm 23 at the rear of the block, that has been moved to an upwardly inclined position when the spikes were first pressed into the ground. Stepping on the arm 23 quickly withdraws the spikes from the ground.

While various changes may be made in the detail construction, it shall be understood that such changes shall be within the spirit and scope of the present invention as defined by the appended claims.

I claim:

1. A starting block comprising a base having an upstanding projection against which a foot may be placed, a foot operated lever having angled arms pivoted upon the base, one of the arms having spikes adapted to be extended through the base and into the ground upon the lever being pivoted, the other arm extending upwardly and rearwardly when the one arm with the spikes is down whereby pressure of the foot upon said last arm will pivot said arm to withdraw the spikes from the ground.
2. A starting block comprising a base having an upstanding projection against which a foot may be placed, a foot operated lever having angled arms pivoted upon the base, one of the arms having spikes adapted to be extended through the base and into the ground upon the lever being pivoted, the other arm extending upwardly and rearwardly when the one arm with the spikes is down whereby pressure of the foot upon said last arm will pivot said arm to withdraw the spikes from the ground, said upstanding portion on the base being rearwardly inclined and having a roughened surface thereon against which the foot can be extended.
3. A starting block as defined in claim 1, and said spikes being rearwardly curved and pointed.
